UNITED STATES PATENT OFFICE.

PHILIP E. MONROE, OF WEYMOUTH, MASSACHUSETTS.

WATER-CLOSET FOR YACHTS AND OTHER SMALL BOATS.

1,139,700.

Specification of Letters Patent.

Patented May 18, 1915.

Application filed July 14, 1914. Serial No. 850,908.

To all whom it may concern:

Be it known that I, PHILIP E. MONROE, citizen of the United States, residing at Weymouth, county of Norfolk, State of Massachusetts, have invented a certain new and useful Improvement in Water-Closets for Yachts and other Small Boats, of which the following is a specification, reference being had therein to the accompanying drawings.

In small yachts and other boats in which the head room is low and the water closet must be located below the water line, difficulty has heretofore been experienced in the construction of water closets that are convenient, on account of the low head room. The closet is usually mounted in the counter of the boat below the water line. As heretofore constructed there has usually been employed a pump or some other suction device for discharging the contents of the bowl into the water.

The object of the present invention is to provide a device which can be installed below the water line and which shall be more especially adapted for use in yachts and other boats where there is low head room.

The closet embodying my invention is applicable to various uses and if desired may be placed above the water line, although primarily intended for use below.

The invention will be fully understood from the following description taken in connection with the accompanying drawings, and the novel features thereof will be pointed out and clearly defined in the claims at the close of the specification.

In the drawings,—Figure 1 is a vertical section of a device embodying the invention and showing the seat and cover closed. Fig. 2 is a plan of the device closed, as in Fig. 1. Fig. 3 is a vertical section on the same line as Fig. 1 but showing the valve opened for discharging the contents. Fig. 4 is a vertical section on a larger scale and partly broken away to show the manner of locking together the operating plunger with the stem of the lower valve. Fig. 5 is a vertical section partly broken away taken at right angles to Fig. 4. Fig. 6 is a horizontal section of the device in the position occupied by the parts before the operating plunger is turned to lock together the piston and the stem of the valve. Fig. 7 is a section on the same line as Fig. 6, showing the parts as

they appear after the operating plunger is turned to lock the parts together, as shown in Fig. 4. Fig. 8 is a detailed view showing the handle of the operating plunger locked in its closed horizontal position sectioned on line 8—8 of Fig. 1. Fig. 9 is a horizontal section on line 9—9 of Fig. 1.

Referring now to the drawings, 1 represents the bowl which is provided with an annular seat 2. The bowl has an opening at the bottom with which is connected a discharge pipe 3 which passes down through the counter of the boat, (not shown) its lower end opening under the water, all the parts being below the water line. The bowl 70 is made very flat and shallow and may be provided with a curved and slanting guide 4, leading from the upper edge of the bowl at the inner periphery of the seat down to the rim of the upper end of the discharge 75 pipe 3 for the purpose of deflecting or directing the matter into the discharge pipe. The seat is provided with a cover or support 5 connected by hinges 6, 6 with the ledge 7 on the upper side of the seat 2.

The part 5 is shown in the form of a cover for the seat, but it performs the more important function of supporting certain of the parts by which the device is operated. I have, therefore, referred to it as a support. The lower end of the discharge pipe 3 is normally closed by a valve 8 as follows:

Secured in the lower part of the pipe 3 is a cross piece 9 which extends diametrically crosswise of the interior of the pipe, the end portions of this cross piece being web-shaped with the broad faces in a vertical position and having in the middle a tubular hub-shaped portion 10. The valve 8 is provided with a tubular stem 11 which extends up through the hub 10 of the cross piece 9 and has a sliding fit therein and is provided on its lower end with a horizontal flange 12. On the lower side of the valve 8, is a disk 13 and the valve 8 is clamped between the flange 12 and the disk 13 by bolts 14 or other suitable devices so that the valve 8 will be securely fastened to the valve stem 11. The discharge pipe 3 is formed with a bead or shoulder 15 on its inner periphery below the cross piece 9 which forms a valve seat and limits the upward movement of the valve 8.

The hollow stem 11 is formed with a vertical elongated slot 16 in opposite sides 110

thereof and a pin 17 extends horizontally through said slot 16 and is secured at its ends to the opposite sides of the discharge pipe 3. A coil spring 18 is mounted within 5 said tubular stem 11, its lower end resting upon said pin 17 and its upper end bearing against the inside of the upper end of the stem 11 so that when the stem 11 is pushed down and thereby the valve 8 is pushed 10 down out of the lower end of the discharge pipe the spring 18 will be compressed, but when the downward pressure is released, the spring 18 will pull the valve back to its uppermost position against the valve seat 15. 15 The pressure of the water on the lower side of the valve 8 together with the spring 18 holds the said valve forcibly against the valve seat and secures a perfect closure at all times. On the upper end of the tubular 20 stem 11 is an upwardly extending shank 19 terminating in a flange or button 20 which is preferably formed with upwardly tapering sides. The said button forms a part of the interlocking connection with the piston, as 25 will be hereinafter described.

While I have described the valve 8 as in the form of a piston operated in part by a spring, I do not limit myself to this construction because I believe that under most 30 conditions other types of valves will operate equally well since the water pressure on the valve is considerable.

The piston is for convenience of construction and assembling, preferably composed of 35 two disks 21, 22 which are made of rubber or other suitable material and are secured to a hollow stem 23 by means of bolts 24 which pass through a washer 25 on the lower side of the disk 22 and pass up through the disks 40 22 and 21 into the flange 26 of the stem 23.

The disk 21 is formed with a recess 27 in its under side which is adapted to receive the head 20 of the button on the upper end of 45 the valve stem 11 when the piston is pushed down, as will be hereinafter described. A short rod 28 has a sliding fit inside of the tubular stem 23 which is provided with a horizontal slot 29 which is engaged by a pin 30 projecting from the side of the rod 28, thus providing for a slight swiveling movement of the rod 28 within the tubular stem 23, but at the same time preventing any 50 vertical movement of the rod 28 within the stem, so that when the rod 28 is lifted or is pushed down the piston will move with it. The rod 28 has a hinge connection 31 with a plunger rod 32 which is provided with an operating handle 33. Surrounding the rod 55 32 is a sleeve 34 which is slidable longitudinally on said rod and is somewhat shorter than the rod 32. A spring 35 is coiled around the said rod 32 near the upper end, one end of said spring bearing against the upper end of the sleeve 34 and the other end 60 65 70 75 80 85 90 95 100 105 110 115 120 125 130

of said spring bearing against a shoulder 36 on the lower end of the shank of the handle 33. This spring is under tension and when the said rod 32 is turned into a vertical position, as shown in Fig. 3, the said spring 70 presses the sleeve 34 down so that its lower end bears against the upper end of the tubular stem 23 of the piston, thus holding rigidly together the rod 32 and the rod 28 so that they will not bend at the joint formed by the hinge, but when it is desired to place the lever in the horizontal position when the rod and piston are at the upper end of their stroke, the rod may be bent at its joint, as shown in Fig. 1, the spring 35 being put under tension.

The cover or support 5 is formed with a hole in which is mounted a circular box or case 37 having a downwardly extending annular flange on its under side into which fits the valve disk 21 and the case is formed with an upwardly extending tubular boss 38 through which the stem 23 has a sliding fit, so that when the piston is drawn into its uppermost position, as shown in Fig. 1, the piston will be within the case with the stem 23 extending up through the boss 38 far enough to bring the joint 31 between the two rods 28 and 32 above the boss 38, so that the rod may be bent at the joint into the position shown in Fig. 1.

A catch is provided whereby the cover or support 5 may be latched down to the seat 2. The means shown are as follows: A spring catch 39 is formed with a bent portion which is secured to the upper side of the cover or support 5 and is formed with a hook 40 which projects down into a recess 41 in the seat 2 and engages with a catch 42 in said recess. The catch is formed with a cam faced bottom and has sufficient elasticity so that when the support 5 is pushed down the hook 40 will snap into engagement with the catch 42. Secured to the spring catch 39 is an upwardly extending member 43 bifurcated at its upper end, forming the fingers 44, 44 which are preferably slightly yielding and are adapted to receive between them the sleeve 34 which surrounds the rod 32 to pinch it with sufficient firmness. When it is desired to turn up the cover or support 5 on its hinge, the hook 40 should be disengaged from the catch 42. Then by lifting on the handle the cover will be raised and turned back on its hinges with the handle. If it is desired simply to turn up the rod 32 into operative vertical position without opening the cover then the handle 43 will be pulled up without first disengaging the catch.

The annular disk 22 which forms a part of the upper piston is formed with a recess in which is a flanged guide having upper and lower flanges 46 between which are held two coöoperating locking plates 47, 48 which 130

are respectively formed with the arc-shaped edges 49, 50, these arc-shaped edges being concentric with the shank 19 of the button 20 and with the rod 28 when the rod 28 is in its normal position. Projecting from the lower end of the rod 28 are two pins 51 and 52 which engage respectively with holes or slots in the plates 47, 48 so that by turning the rod 28 the two locking plates 47 and 48 5 may be moved in opposite directions in their guides, thus bringing the curved edges of the locking plates 47, 48 in toward the shank 19 and under the flange of the button 20, as shown in Figs. 4 and 7. This may be done 10 by partially rotating the rod 32 when the rod 32 is brought into the vertical position and pushed down, as shown in Fig. 3, and as permitted by the horizontal slot 29. When this connection is made, by further pushing 15 down the rod 32 the valve stem 11 and the valve 8 will be pushed down together.

If the parts are in the position shown in Fig. 1 and Fig. 2 with the cover closed and the handle locked, then when it is desired 20 merely to open the cover for use of the closet, the cover will be turned back on its hinges in the manner already described by first releasing the hook 39 from the catch 42 and then lifting on the handle 33 to turn 25 back the cover.

In practice, however, the plunger will ordinarily lift into engagement with the top of the pipe 3, the valve 8 being closed, so that thereby there is no possibility of water 30 in the pipe 8 slopping out of the bowl when the boat is in rough sea. In such case, when it is desired to use the closet the plunger should be lifted and then turned to engage the sleeve 34 with the fork 44 and then the 35 cover should be thrown back as already described. After use the cover should be closed and the cover and plunger locked down. Then, the rod 32 and sleeve 34 will be turned up releasing the sleeve from the 40 fork 44 and without releasing the latch 39 from the catch 42 and without opening the cover, and the rod 32 and sleeve 34 are brought into vertical position. The spring 45 35 will push the sleeve 34 down over the hinge 31 into engagement with the upper end of the tubular stem 23, and the two ends 50 32 and 28 will be held rigidly together. The handle 33 will then be pushed downward, causing the sleeve 34 and rod 32 together 55 with the rod 28 and the piston 21 and parts connected therewith to descend until the annular washer 25 on the under side of the disk 22 strikes on the shoulder at the upper 60 end of the tubular stem 11 in the manner shown in Fig. 4 while the valve 8 is still in its highest position, as shown in Fig. 1. At this stage the locking plates 47 and 48 will 65 not be engaged with the button 20. The operator can readily tell by sense of feeling when the upper piston strikes against the

upper end of the tubular stem 11 of the valve 8. He will then twist the handle 33 to turn the locking plates 47, 48 into engagement with the button and will then continue to push down the rod 32 by means of the 70 handle. By reason of the engagement of the annular washer 25 with the upper end of the stem 11, the stem 11 and valve 8 will be pushed down until the valve 8 is pushed out of the lower end of the discharge tube 3. 75 The matter that has passed from the bowl into the pipe will be pushed down by the upper piston and it will pass out through the lower end of the discharge pipe. The water will rush into the now open end of the 80 pipe and will thoroughly wash out the portion of the pipe which is below the disks 21, 22 which form the upper piston. The said piston has a water-tight fit in the discharge pipe, so that the water cannot rise above it. 85 The plunger rod 32 will then be raised by pulling up on the handle 33, thus lifting the piston disks 21, 22 and valve 8 until both are returned to their normal position, the valve 8 again closing the lower end of the 90 discharge pipe. The space in the discharge pipe between the valve 8 and the piston disk 22 will remain filled with water which will have rushed in, but it cannot rise above the piston 22. It is desirable to have this chamber 95 between the valve 8 and the piston 22 remain filled with water as it keeps the pipe more thoroughly cleansed. In the raising of the plunger rod, as soon as the valve 8 has reached its uppermost position seated 100 against the valve seat 15 the rod 32 should be rotated in a backward direction to release the locking plates 47, 48 from engagement with the button 20 so that the rod 32 and the piston connected therewith may be 105 fully raised to their uppermost position and the rod 32 and sleeve 34 will then be turned down into engagement with the forked clip 44, as shown in Fig. 1, unless it is desired to leave the plunger piston in engagement 110 with the upper end of the pipe 3 to prevent splashing of water out of the bowl as already mentioned.

When the plunger and valve are pushed down, as already described, to discharge 115 the contents of the bowl, the spring 18 will be compressed as shown in Fig. 3, and when the downward pressure is released the expansion of the spring 18 will tend to lift the valve 8 as well as the piston and rod 120 even without any force exerted by the operator. This is intended as a safety attachment so that if by any chance the operator should carelessly turn the rod 32 to unlock the plates 47, 48 while the piston 8 is still 125 in its lowermost position instead of waiting until it has become seated the spring 18 will serve to immediately raise the valve. Otherwise, the lower end of the pipe might remain open and after the upper piston had 130

moved out of the discharge pipe 3 the water would rush in, overflow the bowl and flood the compartment.

In ordinary use of the device, it is desirable to give the piston a second or third complete vertical stroke as thereby the parts will be more thoroughly cleansed and rinsed, and danger of fouling will be lessened.

10. What I claim is:

1. In a water closet for use on boats, a bowl, a discharge pipe leading from said bowl, a valve controlling the discharge opening of the said pipe and a piston normally above the entrance to said pipe but adapted and arranged to descend through the bowl into said pipe, closing it and forcing the contents of it past said valve.

2. In a water closet for use on boats, a bowl, a discharge pipe connected with the bowl, a valve controlling the discharge opening of the said pipe, a support above the bowl, and a piston mounted on the said support normally out of engagement with the said pipe but adapted and arranged to descend through the bowl into the pipe closing it and forcing the contents of the pipe past the said valve.

3. In a water closet for use on boats, a bowl and seat, a discharge pipe connected with the bowl, a valve controlling the discharge opening of the said pipe, a cover for the bowl and seat, a piston mounted on the said cover normally out of engagement with the said pipe but located over it and adapted and arranged to descend into the pipe closing it and forcing the contents of the pipe past the said valve.

4. In a water closet for use on boats, a bowl, a discharge pipe connected with the bottom of the bowl, a valve controlling the discharge opening of the said pipe, a support above the bowl, a piston, a hinged piston rod mounted on the said support and normally lying parallel therewith, said piston being normally out of engagement with the said pipe but located over it and adapted and arranged to descend through the bowl into the pipe closing it and forcing the contents of the pipe past the said valve.

5. In a water closet for use on small yachts and other boats, a bowl, a discharge pipe connected with the bottom of the bowl, a valve which normally closes the outlet of said pipe, a piston which has a sliding fit in said pipe but which is normally above the entrance to said pipe, means for moving said piston down through the bowl into the pipe, and means whereby the downward movement of the said piston within the pipe opens the valve which controls the outlet.

6. In a water closet for use on small yachts and other boats, a bowl, a discharge pipe connected with the bottom of the bowl and open at its lower end, a valve which nor-

mally closes the outlet from said pipe and has an upwardly extending stem, a piston which is normally held above the inlet to the said pipe and at some distance above the said valve stem and is adapted to form a water tight sliding fit in said pipe, means whereby said piston may be moved down through the bowl into said pipe and into engagement with the stem of said valve whereby said valve may be pushed out of the lower end of said pipe, and allow the discharge of matter which has been pushed into the pipe by the piston.

7. In a water closet for use on small yachts and other boats, a bowl, a discharge pipe connected with the bottom of the bowl and open at its lower end, a valve which normally closes the outlet from said pipe and has an upwardly extending stem, a piston which is adapted to slide in said discharge pipe, but which is normally held above the entrance to said discharge pipe, means for operating said piston to cause it to move down through the bowl and enter said pipe and close the passage while the passage is still also closed by the said valve, the further descent of said piston bringing it into engagement with said valve stem and moving the said valve to open the lower end of the pipe to permit the discharge of matter in the pipe which has been pushed down by the piston.

8. In a water closet for use on small yachts and other boats, a bowl, a discharge pipe connected with the bottom of the bowl and open at its lower end, a valve which normally closes the outlet from said pipe and has an upwardly extending stem, a piston which is adapted to slide in said discharge pipe, but which is normally held above the entrance to said discharge pipe, means for operating said piston to cause it to enter said pipe and close the passage while the passage is still also closed by the said valve, and means whereby after a partial descent of said piston it may be locked into engagement with the said valve, the further descent of said piston causing the said valve to pass out of the outlet end of the pipe to permit the discharge of the matter in the pipe which has been pushed down by the said piston.

9. In a water closet for use on small yachts and other boats, a bowl, a discharge pipe connected with the bottom of the bowl and open at its lower end, a valve which normally closes the outlet from said pipe and has an upwardly extending stem, a piston which is adapted to slide in said discharge pipe, but which is normally held above the entrance to said discharge pipe, means for operating said piston to cause it to enter said pipe and close the passage while the outlet passage is still also closed by the said valve, means whereby after a

- partial descent of said piston it may be locked into engagement with the said valve, the further descent of said piston causing the said valve to pass out of the outlet end 5 of the pipe to permit the discharge of the matter in the pipe which has been pushed down by the said piston, a seat which limits the uppermost position of said valve, the said operating means for pushing down 10 said piston being operative also to raise said piston and said connected valve and being operative also to disengage the upper piston from connection with the valve when the valve has reached its seat.
- 15 10. In a water closet for use in small yachts and other boats, a bowl, a discharge pipe connected with the bottom of the bowl, and open at its lower end, a valve which normally closes the outlet from said pipe and has an upwardly extending stem, a piston which is adapted to slide in said discharge pipe, but which is normally held above the entrance to said discharge pipe, means for operating said piston to cause 20 it to enter said pipe and close the passage while the passage is still also closed by the said valve, means whereby after a partial descent of said piston it may be locked into engagement with the said valve, the further descent of said piston causing the valve to pass out of the outlet in the pipe to permit the discharge of the matter in the pipe which has been pushed down by the piston, a seat which limits the uppermost position of said valve, the said operating means for pushing down said piston being operative also to raise said piston and said connected valve and being operative also to disengage the piston from connection 30 with the valve when the valve has reached its seated position, and a spring which is put under tension by the downward movement of said valve and which serves as an auxiliary means of raising said valve to its seat within the discharge pipe when the downward pressure of the piston is released.
11. In a water closet for use on small yachts and other boats, a bowl, a discharge pipe connected with the bottom of the bowl, a valve which normally closes the outlet from said pipe, a piston which has a sliding fit in said pipe but which is normally above the entrance to said pipe, a case for said piston when in its uppermost position above the said pipe, a plunger having a hinged connection with said piston and which is capable of being turned down on its hinge and means for retaining said plunger in its turned down position.
12. In a water closet for use on small yachts and other boats, a bowl, a discharge pipe connected with the bottom of the bowl, a valve which normally closes the outlet from said pipe, a piston which has a sliding fit in said pipe but which is normally above the entrance to said pipe, a case for said piston when in its uppermost position above the said pipe, a plunger having a hinged connection with said piston and which is capable of being turned down on its hinge, means for retaining said plunger in its turned down position.
13. In a water closet for use on small yachts and other boats, a bowl, a discharge pipe connected with the bottom of the bowl, a valve which normally closes the outlet from said pipe, an annular seat above the bowl, a piston which has a sliding fit within said discharge pipe, a hinged support above the seat, said support having a downwardly extending annular flange within which said piston is normally retained, an upwardly projecting tubular stem for said piston, the support being formed with a guide opening through which the said stem passes, a rod loosely fitting within said tubular stem and projecting above the top of the stem, means for connecting said rod with said tubular stem so constructed and arranged that said rod has a partial rotary movement therein but is restrained from vertical movement with relation thereto, a plunger rod having a hinged connection with said first rod above the tubular stem of said piston and which permits the said plunger rod to be turned down into angular relation to the said first rod, said plunger rod being also adapted to be turned into alignment with said rod to which it is hinged and pushed down through the guide opening in said piston case and thereby to push down the said piston with which it is connected into the said discharge pipe, and means whereby the continued downward movement of the said plunger and connected piston after it has entered the discharge pipe causes the outlet valve to move out of the discharge pipe.
14. In a water closet for use on small yachts and other boats, a bowl, a discharge pipe connected with the bottom of the bowl, a valve which normally closes the outlet from said pipe, an annular seat above the bowl, a piston which has a sliding fit within said discharge pipe, a hinged support above the seat, said support having a downwardly extending annular flange within which said piston is normally retained, an upwardly projecting tubular stem for said piston, the support being formed with a guide opening through which the said stem passes, a rod loosely fitting within said tubular stem and projecting above the top of the stem, means for connecting said rod with said tubular stem so constructed and arranged that said rod has a partial rotary movement therein but is restrained from vertical movement with relation thereto, a plunger rod having a hinged connection with said first rod above the tubular stem of said piston and which permits the said plunger rod to be turned down into angular relation to the said first rod, said plunger rod being also adapted to be turned into alignment with said rod to which it is hinged and pushed down through the guide opening in said piston case and thereby to push down the said piston with which it is connected into the said discharge pipe, and means whereby the continued downward movement of the said plunger and connected piston after it has entered the discharge pipe causes the outlet valve to move out of the discharge pipe.

from the said pipe, an annular seat above the bowl, a piston which has a sliding fit within said discharge pipe, a hinged support above the seat, said support having a 5 downwardly extending annular flange within which said piston is normally retained, an upwardly projecting tubular stem for said piston, the support being formed with a guide opening through which the said stem 10 passes, a rod loosely fitting within said tubular stem and projecting above the top of the stem, means for connecting said rod with said tubular stem so constructed and arranged that said rod has a partial rotary 15 movement therein but is restrained from vertical movement with relation thereto, a plunger rod having a hinged connection with said first rod above the tubular stem of said piston and which permits the said 20 plunger rod to be turned down into annular relation to the said first rod, said plunger rod being also adapted to be turned up into alinement with said rod to which it is hinged and pushed down through the guide 25 opening in said piston case and thereby to push down the said piston with which it is connected into the said discharge pipe, a sleeve loose on said plunger which is somewhat shorter than the plunger so that when 30 the plunger is in its turned down position the sleeve will not cover the said hinge, means which when the plunger is turned into its vertical position causes said sleeve to move down into abutting engagement with the tubular stem of the piston and to inclose the said hinge so as to retain the plunger and the rod to which it is hinged in rigid connection, means whereby the continued 35 downward movement of the said plunger and connected piston after it has entered the discharge pipe causes the valve to move out of the discharge pipe, and a clip attached to said hinged support and with which said plunger is yieldingly connected when in its 40 turned down position but which is releasable therefrom.

15. In a water closet for use on small yachts and other boats, a bowl, a discharge pipe connected with the bottom of the bowl, a valve which normally closes the outlet from the said pipe, an annular seat for the bowl, a piston which has a sliding fit within said discharge pipe above the said valve, a hinged support having a downwardly extending annular flange within which said piston is normally retained, an upwardly projecting tubular stem for said piston, the 45 said support being formed with a guide opening for said stem, a rod loosely fitting within said tubular stem and projecting above the top of the stem, means for connecting said rod within said tubular stem so constructed and arranged that said rod has a partial rotary movement therein but is restrained from vertical movement with relation thereto, a plunger rod having a hinged connection with said first rod above the tubular stem of said piston and which permits the said plunger rod to be turned 50 down into angular relation to the said first rod, said plunger rod being adapted to be turned into alinement with said rod to which it is hinged and pushed down through the guide opening in said piston case and thereby to push down the said piston with which it is connected into the said discharge pipe, a sleeve loose on said plunger which is somewhat shorter than the plunger so that when the plunger is in its turned down position the sleeve will not cover the said hinge, means which when the plunger is turned into its vertical position causes said sleeve to move down into abutting engagement with the tubular stem of the piston 55

16. In a water closet for use on small yachts and other boats, a bowl, a discharge pipe connected with the bottom of the bowl, a valve which normally closes the outlet from the said pipe, an annular seat for the bowl, a piston which has a sliding fit within said discharge pipe above the said valve, a hinged support having a downwardly extending annular flange within which said piston is normally retained, an upwardly projecting tubular stem for said piston, the 60 said support being formed with a guide opening for said stem, a rod loosely fitting within said tubular stem and projecting above the top of the stem, means for connecting said rod within said tubular stem so constructed and arranged that said rod has a partial rotary movement therein but is restrained from vertical movement with relation thereto, a plunger rod having a hinged connection with said first rod above the tubular stem of said piston and which permits the said plunger rod to be turned 65 down into angular relation to the said first rod, said plunger rod being adapted to be turned into alinement with said rod to which it is hinged and pushed down through the guide opening in said piston case and thereby to push down the said piston with which it is connected into the said discharge pipe, a sleeve loose on said plunger which is somewhat shorter than the plunger so that when the plunger is in its turned down position the sleeve will not cover the said hinge, means which when the plunger is turned into its vertical position causes said sleeve to move down into abutting engagement with the tubular stem of the piston 70

plunger rod to be turned down into angular relation to the said first rod, said plunger rod being also adapted to be turned up into alinement with said rod to which it is hinged and pushed down through the guide 75 opening in said piston case and thereby to push down the said piston with which it is connected into the said discharge pipe, a sleeve loose on said plunger which is somewhat shorter than the plunger so that when the plunger is in its turned down position the sleeve will not cover the said hinge, means which when the plunger is turned into its vertical position causes said sleeve to move down into abutting engagement with the tubular stem of the piston and to inclose the said hinge so as to retain the plunger and the rod to which it is hinged in rigid connection, means whereby the continued 80 downward movement of the said plunger and connected piston after it has entered the discharge pipe causes the valve to move out of the discharge pipe, and a clip attached to said hinged support and with which said plunger is yieldingly connected when in its 85 turned down position but which is releasable therefrom.

16. In a water closet for use on small yachts and other boats, a bowl, a discharge pipe connected with the bottom of the bowl, a valve which normally closes the outlet from the said pipe, an annular seat for the bowl, a piston which has a sliding fit within said discharge pipe above the said valve, a hinged support having a downwardly extending annular flange within which said piston is normally retained, an upwardly projecting tubular stem for said piston, the 90 said support being formed with a guide opening for said stem, a rod loosely fitting within said tubular stem and projecting above the top of the stem, means for connecting said rod within said tubular stem so constructed and arranged that said rod has a partial rotary movement therein but is restrained from vertical movement with relation thereto, a plunger rod having a hinged connection with said first rod above the tubular stem of said piston and which permits the said plunger rod to be turned 95 down into angular relation to the said first rod, said plunger rod being adapted to be turned into alinement with said rod to which it is hinged and pushed down through the guide opening in said piston case and thereby to push down the said piston with which it is connected into the said discharge pipe, a sleeve loose on said plunger which is somewhat shorter than the plunger so that when the plunger is in its turned down position the sleeve will not cover the said hinge, means which when the plunger is turned into its vertical position causes said sleeve to move down into abutting engagement with the tubular stem of the piston 100

- and inclose the said hinge so as to retain the plunger and the rod to which it is hinged in rigid connection, means whereby the continued downward movement of the said 5 plunger and connected piston after it has entered the discharge pipe causes the outlet valve to move out of the discharge pipe, a clip attached to said support and with which said plunger is yieldingly connected when 10 in its turned over position, but which is releasable therefrom, and a latch connection between said hinged support and said seat whereby the support and seat may be retained in connection with each other and 15 allow the said plunger to be turned up on its hinge without raising the support, said latch being capable of being released from the seat so that the said support and the plunger may be together turned on their 20 hinges.
17. In a water closet for use on small yachts and other boats, a bowl, a discharge pipe connected with the bottom of the bowl, a valve which normally closes the outlet 25 from said pipe and has an upwardly extending stem, said stem being formed with a laterally extending flange on its upper end, a piston which is normally held above the inlet from the bowl to the said pipe and is 30 adapted to form a water tight sliding fit in said pipe, a plunger connected with said piston whereby said piston may be moved down into said pipe, said piston being formed with a recess in its under side which 35 is adapted to receive the said flange on said lower piston stem, movable locking plates mounted in the recess in said piston which are movable into and out of engagement with said flange on the stem of the outlet 40 valve to lock and unlock the said piston and valve with relation to each other, and means connected with said plunger whereby said locking plates are moved into said locking and interlocking position.
- 45 18. In a water closet for use on small yachts and other boats, a bowl, a discharge pipe connected with the bottom of the bowl, a valve which normally closes the outlet from said pipe and has an upwardly extending stem, said stem being formed with a laterally extending flange on its upper end, a piston which is normally held above the inlet from the bowl to the said pipe and is 50 adapted to form a water-tight sliding fit in said pipe, said piston being formed with a recess in its under side which is adapted to receive the said flange on said lower piston stem, movable locking plates mounted in the recess in said upper piston which are 55 movable into and out of engagement with said flange on the stem of the outlet valve to lock and unlock the said piston and valve with relation to each other, a tubular stem for said piston, a plunger rod passing 60 through said tubular stem and having a 65 swivel connection with said tubular stem which permits partial rotation of said rod within said tubular stem and which holds the said rod in connection with said stem so that their longitudinal movement will be 70 together, said plunger rod being vertically reciprocable to move said upper piston down into said discharge pipe and raise it out of said discharge pipe, and means whereby after it has been moved down to bring 75 the said flange on the stem of the lower piston into the recess in the piston said locking plates may be actuated by the rotation of said rod to bring them into locking engagement with the flange on the stem of 80 the lower piston.
19. In a water closet for use on small yachts and other boats, a bowl, a discharge pipe connected with the bottom of the bowl and open at its lower end, a piston and a 85 valve, one above the other, which have a sliding fit in said discharge pipe, means for actuating said piston and valve whereby the piston may be moved down into the discharge pipe and up out of the discharge 90 pipe, and whereby the valve may be moved down out of the lower end of the discharge pipe and back into the discharge pipe, and means controlling the relative positions of said piston and valve so that whenever 95 either the piston or the valve is out of the discharge pipe the other of said two members will be within the discharge pipe.
20. In a water closet for use on small yachts and other boats, a bowl, a discharge 100 pipe connected with the bottom of the bowl and open at its lower end, a piston and a valve, one above the other, which have a sliding fit in said discharge pipe, means for actuating said piston and valve whereby 105 the piston may be moved down into the discharge pipe and up out of the discharge pipe and whereby the said valve may be moved down out of the lower end of the discharge pipe and back into the discharge 110 pipe, means controlling the relative positions of said piston and valve so that whenever either said piston or said valve is out of the discharge pipe and the other of said two members will be within the discharge 115 pipe, a separable connection between said piston and valve controlled by the operator and a plunger connected with said piston whereby when the said piston and valve are locked together the said plunger actuates 120 both the said piston and said valve.
21. In a water closet for use on small yachts and other boats, a bowl, a discharge pipe connected with the bottom of the bowl and open at its lower end, a plunger and a 125 valve, one above the other, both of which have a sliding fit in said discharge pipe, a separable connection between said plunger and said valve, means for actuating said plunger and valve whereby the plunger may 130

be moved down into the discharge pipe and up out of the discharge pipe and whereby the valve may be moved down out of the lower end of the discharge pipe, the relative 5 positions of said plunger and valve being such that whenever either the plunger or the valve is out of the discharge pipe the other will be within the discharge pipe.

22. In a water closet for use on boats, a 10 bowl, a discharge pipe connected with the bowl, a valve controlling the discharge opening of the said pipe, and a piston normally out of engagement with the said pipe and with said valve and having a range of 15 movement while said valve is stationary but adapted and arranged to descend into the pipe closing it and opening said valve and forcing the contents of the pipe past the said valve.

20 23. In a water closet for use on boats, a bowl, a discharge pipe connected with the bowl, a valve controlling the discharge opening of the said pipe, a support above the bowl and a piston mounted on said 25 support normally out of engagement with said pipe but adapted and arranged to descend into the pipe through the bowl thereby closing the pipe and forcing the contents of the pipe past the said valve, the 30 said support being movable to carry the said piston up and back away from the bowl.

24. In a water closet for use on boats, a 35 bowl and seat, a discharge pipe connected with the bottom of the bowl, a valve controlling the discharge opening of the said

pipe, a hinged support above and at one side of the seat, a piston, a hinged piston rod mounted on the said support and normally lying parallel therewith, said piston being normally out of engagement with the said pipe but located over it and adapted and arranged to descend through the bowl into the pipe closing it and forcing the contents of the pipe past the said valve, said hinged support being adapted to be turned back on its hinge and thereby carry the said piston and piston rod off to one side and away from the bowl.

25. In a water closet for use on small 50 yachts and other boats, a bowl, a discharge pipe connected with the bottom of the bowl, a valve which normally closes the outlet of said pipe, a hinged support above and at one side of the bowl, a piston which is 55 mounted in said support and which has a sliding fit in said pipe but which is normally above the entrance to said pipe, means for moving said piston down through the 60 bowl into the pipe, and means whereby the downward movement of the said piston within the pipe opens the valve which controls the outlet, said hinged support being adapted to be turned back on its hinge and thereby carry said piston off to one side of 65 the bowl.

In testimony whereof I affix my signature, in presence of two witnesses.

PHILIP E. MONROE.
